UNITED STATES PATENT OFFICE.

DUANE F. HOLT, OF NASHUA, NEW HAMPSHIRE.

DESIGN FOR A KITCHEN-TABLE.

SPECIFICATION forming part of Design No. 31,722, dated October 24, 1899.

Application filed August 28, 1899. Serial No. 728,797. Term of patent 14 years.

To all whom it may concern:

Be it known that I, DUANE F. HOLT, a citizen of the United States, residing at Nashua, in the county of Hillsborough and State of New Hampshire, have invented and produced a new and original Design for Kitchen-Tables; and I do hereby declare the following to be a full, clear, and exact description of the same, reference being had to the accompanying drawing, forming a part thereof.

In the accompanying drawing the figure is a perspective view of a table constructed in accordance with my design.

The leading feature of my design consists in a rectangular-shaped table having a flat top surface and open framework composed of legs and braces and horizontally-sliding boards, drawers, and compartments.

In the drawing, A represents the frame-work of the table, which is rectangular in shape, as shown, and open, the said framework comprising four legs a and suitable connecting-braces a' .

a^2 represents a connecting and supporting bottom board.

The framework is provided with sliding drawers a^5 .

a^6 a^8 represent horizontally-sliding boards, and a^7 a^9 represent horizontally-sliding compartments.

The top of the table is flat and is provided with a central strip or slab a^9 , constructed of stone or other suitable material.

Having now described my invention, what I claim as new, and desire to secure by Letters Patent, is—

The design for a kitchen-table, substantially as herein shown and described.

In testimony whereof I hereunto affix my signature in presence of two witnesses.

DUANE F. HOLT.
